UNITED STATES PATENT OFFICE.

JOSIAH C. COBB, OF WASHINGTON, DISTRICT OF COLUMBIA.

LOADING APPARATUS.

No. 881,774.

Specification of Letters Patent. Patented March 10, 1908.

Application filed June 10, 1907. Serial No. 378,261.

To all whom it may concern:

Be it known that I, JOSIAH C. COBB, a citizen of the United States, residing at Washington, in the District of Columbia, have invented certain new and useful Improvements in Loading Apparatus, of which the following is a specification.

This invention relates to loading apparatus in general and more particularly to an improved machine for loading earth, gravel or the like into wagons, and especially to provide a light portable hoisting machine to be so manipulated that it can be loaded by wheel scrapers or three horse slide scrapers working abreast and kept near where these scrapers take the earth and when loaded to be constructed in such a manner that when hoisted the platform upon which the earth is dumped will automatically form itself into a chute which can be dumped into a wagon or other suitable conveyance. Said apparatus is so constructed that no part of the earth thereon is permitted to fall wide of the wagon, thus causing a loss of labor, offering a hindrance to the continuous operation of the machine and loss of time.

A further object of the invention is to provide means for supporting the platform in such a manner from more than one point that there can be no swing, or so little, to the platform that there will be no inaccuracy to the discharge of earth from said platform.

A further object of the invention is to provide an apparatus which by reason of its lightness can be gotten into places where a steam shovel can not be taken without great cost.

A further object of the invention is to provide an apparatus which can be manufactured and sold far below the cost of a steam shovel.

Another feature of the invention is in the fact that the platform does not offer a dead weight to the hoisting engine and elevating parts of the machine, there being an upward swing of the outer portions of the platform prior to the full load being lifted; this brings a less sudden strain on said elevating mechanism.

In order that my invention may be more thoroughly understood I have clearly illustrated one form thereof in the accompany-

ing drawings and a full and exact description of the same is contained in the annexed specification.

In the accompanying drawings, Figure 1 is a side elevation of the device, Fig. 2 is an end view, Fig. 3 is a top plan view, and, Fig. 4 is a view of the platform as seen from the opposite side of Fig. 1.

In the several views like numerals of reference designate similar parts of my improved apparatus.

In the drawings, 1 designates a metal frame made preferably of channel iron, 2 a flooring partly covering said frame, and 3 wheels on which the frame is mounted for ready transportation.

4 designates an ordinary hoisting engine having a double drum 5, mounted on said frame, over which double drum the hoisting ropes are wound.

Mounted on the frame 1 are parallel cranes 6, 6 having braces 7, 7 and journaled on the shaft 8 in the extreme upper ends of the cranes are pulleys 9, 9. Pulleys 10, 10 journaled on shaft 11, and pulleys 12, 12 journaled on shaft 13 are mounted in the cranes on which the hoisting cables are designed to travel.

The elevating platform 14 in the form shown is composed of a central section 15, two side sections 16, 16 hinged to the central section as shown at 17, 17, said side sections having upturned rigid portions 18, 18 having 85 rolled edges as at 19 for the purpose of strengthening them longitudinally.

Staples 20 secured to the hinged sections 16 of the platform form attaching means for portions 21 of the elevating chains 22 above 90 the platform, while chains 23 of proper length are secured to said staples 20 beneath the platform to control the amount of the collapse of the platform and consequently the width of the floor of the contents of said 95 platform.

In operation the platform 14 is lowered to rest flat on the ground as shown in dotted lines Fig. 2, the elevating chains are held a little to one side while several scraper loads 100 of earth are dumped on the platform, the hoisting engine then starts to elevate the platform, at first bringing the parts 16 up to the position shown, then the whole platform

is lifted, this gradual taking up of the whole weight is less shock to the elevating parts. After the platform is elevated to the proper height one hoisting chain or the other as preferred is stopped, while the other continues, which tilts the platform and discharges the earth into any suitable receptacle or conveyance.

The shift of the work of the scrapers is followed by the loader, thus avoiding a long haul for the scrapers, which is very expensive.

I am aware of patents on dumping and elevating platforms but they are not practical for the following reasons: If the platform is made wide enough to drive the largest wheel or three horse slide scrapers working abreast thereon, said platform will not deposit all of said earth into a wagon but my improved platform is so constructed as to form a chute that can be regulated to discharge all of its contents properly, and it is for this feature I claim my principal improvement.

25 What I claim and desire to secure by Letters Patent is:

1. A hoisting platform, comprising a solid central section open at each end, side sections connected thereto, and means for raising the platform bodily and then tilting said platform longitudinally, whereby the contents thereof is discharged through one of said open ends.

2. A loading apparatus, comprising a platform, composed of a material-containing portion open at each end, side sections for retaining the material on the platform movable with respect to the material-containing portion, and means for hoisting said platform, including connections to said sections for first moving the same with respect to the material-containing portion and subsequently raising the platform bodily and then tilting said platform longitudinally, whereby the contents thereof is discharged through one of said open ends.

3. A loading apparatus, comprising a platform, composed of a material-containing portion open at each end, side sections for retaining the material on the platform movable with respect to the material-containing portion, means for hoisting said platform, including connections to said sections for first moving the same with respect to the material-containing portion and subsequently raising the platform bodily, and then tilting said platform longitudinally, whereby the contents thereof is discharged through one of said open ends and means for limiting the movement of said section.

4. A chute for-loading apparatus, comprising a central flat portion, side sections relatively movable with respect thereto, and

hoisting devices connected to the side sections and central portion for first moving the side sections radially with respect to the central portion and then bodily raising the chute and then tilting said platform longitudinally, whereby the contents thereof is discharged through one of said open ends.

5. A collapsible hoisting platform comprising a plurality of sections hinged together, the sections at opposite sides of said platform having upturned portions.

6. A collapsible hoisting platform, comprising a plurality of sections hinged together, the sections at opposite sides of said platform being upturned, the edges of said upturned sections being rolled.

7. A normally flat hoisting platform, comprising a solid central section open at each end, side sections pivotally connected thereto, and means connected to said side sections for collapsing the same towards each other and limiting such movement to form a chute.

8. A normally flat hoisting platform, comprising a solid central section open at each end, side sections pivoted thereto, means extending between said side sections and connected to a hoisting device for collapsing, and means for limiting the inward travel of said sections to form a chute and a hoisting device for bodily lifting said chute and then tilting the same longitudinally, whereby the contents thereof is discharged through one of said open ends.

9. A collapsible hoisting platform, comprising a plurality of separate sections hinged together, and a flexible band secured at its ends to the outside sections of said platform and extending transversely across the intermediate sections thereof, whereby the swinging movement of said hinged sections is limited.

10. A collapsible hoisting platform, comprising a plurality of sections hinged together, a flexible strap extending across the under side of said platform transversely of the hinged sections thereof, and having its ends secured to the outside sections of the platform, and a plurality of flexible straps extending transversely across the upper side of said platform, each of said straps being secured at their ends to the outside sections of the platform.

11. The combination with a collapsible hoisting platform, having open ends adapted to form a chute when raised, of means for successively lifting said platform bodily and tilting said platform longitudinally, to discharge the contents thereof through one of said open ends.

12. The combination with a collapsible hoisting platform, having open ends adapted to form a chute when lifted, of hoisting mechanism having a pair of cranes and hoist-

ing cables passing over said cranes, said hoisting cables being attached to said platform adjacent to the opposite ends thereof for bodily lifting the same, and for tilting
5 said chute longitudinally, whereby the contents thereof is discharged through one of said open ends.

In testimony whereof I affix my signature in presence of two witnesses.

JOSIAH C. COBB.
